PRESSURE BLOWER

Theodore L. Menge, Shreveport, La., assignor of one-fourth to A. F. Flournoy and one-fourth to Pike Hall, both of Shreveport, and one-eighth to Wilson Edward Campbell, Caddo Parish, La.

Application June 23, 1945, Serial No. 601,167

5 Claims. (Cl. 230—138)

1

My invention relates to blowers and, but more specifically to improved blade mechanisms for housing incased blowers.

Before entering into a discussion of my invention in blower mechanisms, to enable the reader to better understand its operation and to better explain its departure from the teachings of the prior arts concerned with blowers, I will enter into a discussion of the mode of operation of my invention in blowers in comparison with the mode of operation of prior art types of blowers with which it is most nearly related.

Blowers may be roughly classified in two classes. The first is the class which we call the propeller class, to which class belong the well known household fans, the ceiling type fan and the buzz type fan. In this first propeller class of fan the blades are extended in radial directions from a common shaft in an arrangement where the blades are set at angles with respect to the common shaft and also set at angles to their plane of rotation. When this type of fan operates to push air, the blades may be said to slide through the volume of air it is pushing.

In the second class of blower with which my blower is to be compared, the blades, more often referred to as vanes, are extended in radial directions with respect to a common axle and lie in planes passing through their axis of rotation. Some blowers of this type have their blades curved in their lengthwise direction. Some are curved in their widthwise direction while others are curved in both their lengthwise and widthwise directions.

In some types of this second class of blowers the vanes proper commence at the axle to which they are joined and with which they rotate, while in others the vane areas commence at a radial distance from their common axle and are mounted on it by means of spiders or the like.

In this second class of blower, as in the first class, all of the vanes are fixed to a common shaft in fixed relationship to one another so that all the vanes rotate as a unit. All of this second class of blowers, hereinafter referred to as centrifugal blowers, as far as applicant knows, operate upon a principle that makes use of centrifugal force alone imparted to volumes of air confined between the radially extending vanes as the force applied in impelling a stream of air.

In the centrifugal blower as known to the prior art, the air is taken into the blower in a direction along the axle to which the vanes are attached. In some styles of these centrifugal blowers, air is taken in from one end of the axle of rotation

2

of the blower while in the other styles the air is brought in at both ends of the axle.

The blower of my invention also makes use of centrifugal force applied to the volume of air between its vanes, but it also applies other forces to the stream of air it impels, as will be explained hereinafter.

Each blade of my blower is separately, rotatably mounted on a common blower blade axle, 10 preferably through means of a pair of mother bearing collars rotatably mounted on the cross bar in which the blades are pivotably mounted. The blower shaft is held stationary and the blades are separately revolved about it. Each blade 15 is made to revolve through a cycle of speeds, progressively increasing from a minimum speed to a maximum speed and then progressively decreasing down again to the minimum speed.

The reader will appreciate that my type of 20 blower, even considered as having but one blade, will produce a blowing action since the volume of air in front of the blade is brought up to the maximum speed of the blade after which it continues to move away from the blade under its 25 own momentum while the blade is slowing down.

An object of my invention is to provide a blower adapted to work against a head pressure.

Another object of my invention is to provide a blower capable of drawing air into its intake 30 side at subatmospheric pressures and one capable of discharging air from its exhaust side against a substantial head pressure.

Another object of my invention is to provide a blower mechanism that operates on the principle 35 of pushing air in a manner similar to the pushing action of a piston in a cylinder.

Another object of my invention is to provide a blower mechanism in which the slip incidental to its operation is reduced to a minimum.

40 Other objects and advantages of my invention will appear in my hereinafter following detailed description of my blower mechanisms illustrated in the accompanying drawings in which:

Figure 1 is a vertical side elevational view, partially broken, of a preferred form of blower mechanism embodying my invention.

Fig. 2 is a broken vertical side elevational view of the mechanism illustrated in Fig. 1;

Fig. 3 is a vertical cross sectional view of the 50 mechanism illustrated in Fig. 2 taken on line 3—3 of Fig. 1 as viewed from the right end of Fig. 1;

Fig. 4 is a diagrammatic view illustrating the operation of the preferred form of blower;

Fig. 5 is a diagrammatic view illustrating the 55 operation of the preferred form of blower;

Fig. 6 is a broken side elevational view of a modified form of blower embodying my invention;

Fig. 7 is a fragmentary view illustrating an adjustable part of the structure illustrated in Fig. 6;

Fig. 8 is a diagrammatic view illustrating the operation of the modified form of blower illustrated by Fig. 6; and,

Fig. 9 is a diagrammatic view illustrating the operation of the modified form of blower illustrated by Fig. 6.

Referring to Figs. 1, 2 and 3 of the drawings, numeral 10 designates generally the frame portion of my blower comprising a base 11 on which a pair of side frames 12 are mounted in vertical positions parallel to each other and bolted to the base 11 with bolts 13.

The blower mechanism proper is supported on the top members 14 of the side frames 12 by means of the shaft bearings 35. The housing 15, made up of a main body portion 16 and a housing extension 17, is attached directly to the base 11 by means of its rear feet 18 and its forward feet 19. A crown 20 positioned at the top of the housing 15 and a pan 21 positioned at the bottom of the housing 15 are rotatably, adjustably mounted and supported by the means of a pair of spiders 24 secured to the shaft 30 by means of set screws 25. The shaft 30, the spiders 24, the crown 20 and the pan 21 form a unit and as a unit are adjustably rotatably mounted on the stud portions 33 of the shaft 30.

Each spider 24 is provided with a pair of upwardly extending arms 26 positioned outside of the housing 15. The upwardly extending arms 26 carry crown supporting fingers 28 that extend inwardly into the housing 15 through the crown finger slots 22. The lower pair of downwardly extending arms 27 of the spider 24 are provided with pan supporting fingers 29 extended through the pan finger slots 23 to support the pan 21 at the bottom of the housing 15.

All of the moving parts of my fan mechanism which will hereafter be mentioned and also the above described spiders 24 are carried by the shaft 30 which is made in the shape of a crank shaft. The shaft 30 is made up of two stud shafts 33 extending outwardly from the center of disc portions 34 and a cross bar 32 threaded to the disc portions 34. The outer ends of the stud shafts 33 terminate in squared end portions 31. The shaft 30 is rotatably mounted in the pair of split bearings 35 attached to the top members 14 of the frames 10.

Before going further with my description, I want to say that the shaft 30 does not turn during the operation of the blower although it is adjustably mounted in the bearings 35. It is adapted to be locked in a set position by means of the locking arms 36 fitted to the squared ends 31 of the shaft 30. The slotted end portions 37 of the locking arms 36 are clamped to the calibrated slotted segments 38 forming parts of the side frames 12 by means of bolts 39 and wing nuts 40. By this means of adjustment, the cross bar 32 of the shaft 30 may be set in various angular adjusted positions with respect to the vertical plane passing through the stud shaft portions 33 of the shaft 30 resting in the bearings 35.

The angular position of adjustment of the cross bar 32 is dictated by the R. P. M. of the blades 43 themselves due to the fact that for more efficient operation the shaft 30 should be adjusted to a critical angle dependent upon the R. P. M. of the blades 43. The higher the R. P. M. of the

blades 43, the farther back from the vertical center position the cross bar 32 should be set for reasons that will be made clear to the reader further on in this specification.

5 The blades 43 including their guide rods 44 are rotatably mounted on the cross bar 32 through the means of mother bearing collars 41 which are rotatably mounted on the cross bar 32. The mother bearing collars 41 are each provided 10 with six equally circumferentially spaced stud shaft bearings 42 in which the six blades 43 themselves are pivotally mounted by means of their blade supporting shafts 45. The mother bearing collars 41 and the blades 43 assembled in them should be placed on the cross bar 32 before it is screwed into the disc portions 34 of the shaft 30 during the assembly of the shaft 30.

The guide rods 44 of the blades 43 are extended perpendicularly outwardly from the blade supporting shafts 45 at their centers.

The blades 43 are rotated by means of the cage 48. The cage 48 is rotated through the means of the driving pulley 50 secured to the left hand side plate 49 and the driving belt 51 extended 25 over the driving pulley 50 from a source of power not shown. The cage 48 is made up of a pair of side plates 49 joined together by spacing rods 54 that are fastened into circular rim portions 53 of the side plates 49. The side plates 49 have 30 centrally depressed portions 52 shaped to accommodate the disc portions 34 of the shaft 30. The side plates 49 revolve about the disc portions 34 which are held stationary. This construction is adopted to prevent air from being blown back 35 from the pressure side of the blower to the intake side of the blower when the blower operates against a head pressure as will be explained hereinafter.

The side plates 49 of the cage 48 are spaced 40 outwardly from the disc portions 34 by the spacing rods 54. The cage 48 is rotatably mounted on the stud shafts 33 by means of a pair of roller bearings 55.

The blades 43 are connected to the cage 48 by means of rocker arms 56 which are pivotally mounted in side plates 49. Each rocker arm 56 includes a push bar 57 extending perpendicularly from its center. In the fork shaped end 58 of each push bar 57 a knuckle slide bearing 59 is 50 pivotally mounted by means of a pair of pivot bolts 60. The knuckle slide bearings 59 embrace the guide rods 44 forming parts of the blades 43 which guide rods are spaced from the rear sides of the blade webs 46 by means of the web spacing brackets 47 bolted to the outer ends of the guide rods 44. This spacing gives room for the knuckle bearings 59 to slide along the guide rods 44 back and forth during the operation of the blower.

Before the blower can be operated the rocker arms 56 must be locked into adjusted positions by means of the rocker arm locking mechanism 61. It is through this mechanism that the capacity of this preferred type of blower is changed within limits as will be explained later.

65 The locking mechanism 61 is made up of the right and left slotted ring shaped locking plates 62 supported by the slotted fingers 63 by means of the stud pins 64 secured in the locking mechanism 61.

The locking mechanism 61 is made up of the right and left slotted ring shaped locking plates 62 mounted in surrounding positions over the right and left studs 33 respectively of the shaft 30. The locking plates 62 are supported by means of stud pins 64 secured to the same which extend

through the slotted fingers 63. The slotted fingers 63 are secured to the outer ends of the rocker arms 56 which are rotatably mounted in the side plates 49. The push bars 57, forming integral parts of the rocker arms 56, may be rotated in unison outwardly or inwardly by rotating the locking plates 62. When the proper setting of the push bars 57 is determined, they are held in such a setting by clamping the locking plates 62 to the side plates 49 of the cage 48 by means of the clamping bolts 65 and the clamping nuts 66. When the clamping nuts 66 are screwed down tightly, the slotted plates 62 turn with the side plates 49.

The effective working radius of the cage 48 is the radial distance from its axis of rotation O_c to the extended tip end of a push bar 57, the distance k shown in the diagrammatic view, Fig. 5 of the drawings, position of the axis of rotation of a knuckle slide bearing 59 which is pivotally mounted in the tip end of the push bar 57. When all of the push bars 57 are evenly adjusted, their tip ends lie in a circle whose radius is k . It is pointed out here to the reader, however, that all of the tip ends of the push bars 57 do not have to lie in a common circle for my preferred form of fan to operate. So long as no two blades 43 of the blower strike each other at any position in their revolutions about the cross bar 32, the fan will operate.

It is due to the fact that the guide rods 44 are permitted to slide through the knuckle slide bearings 59 that this preferred form of blower fan operates in which operation the cage 48 revolves about an axis O_c while the blades 43 are revolved about another axis O_f . It is pointed out here to the reader that the feature of the slide bearing 59 and the guide rod 44 on which it slides is itself not essential in the construction of a blower mechanism embodying my invention. Further on in this specification there will be described a blower mechanism embodying my invention in which will be found no reciprocating parts at all.

In my blower as illustrated in my drawings, the blower mechanism proper, that is to say the blower mechanism with the entire housing 15 removed, will still operate efficiently as a blower and will operate in the following manner. The principal volume of air being drawn into my blower travels in a direction at right angles to the vertical plane extended through its axis of rotation O_f of the blades 43 from the supporting structure and is discharged through the opposite side of the blower in a direction at right angles to the same plane. However, the discharged air is expelled, as nearly as could be determined from observing the operation of a working model of the same, in a generally diverging wedge shaped pattern.

With the housing 15 removed, a small portion of the air drawn into the blower was seen to be drawn in directions endwise to the blades 43 in the opening movement of the blades 43 and a small portion of the discharged air was seen to be expelled in endwise directions of the blades 43. In an experiment with this model where side walls were placed close to the ends of the blades 43, the intake stream of air was substantially all channelled in a straight line direction perpendicular to the vertical plane passing through the axis of rotation O_f from the supporting structure and the discharged air was expelled in a better defined wedged shaped pattern.

The blades 43 of my blower at any given mo-

ment will be observed to move at different speeds although each one is carried through the same cycle of speeds as explained above. To make this clearer to the reader, I will say that during a part of the rotation of a pair of adjacent blades 43, the leading blade 43 will be seen to outrun the following blade 43 until such time that the maximum angle of opening between the adjacent blades 43 has occurred. This opening movement of the blades may be thought of as the intake stroke of my blower. After the maximum angle of opening has been reached, the following blade, even though it starts slowing down, approaches the blade ahead of it because the blade ahead of it is slowing down at a greater rate and finally comes to it by the angular distance measured by the minimum angle of opening. This closing movement of the blades 43 may be thought of as the discharge stroke of my blower. The reader will now appreciate that my blower in addition to operating on the principle of centrifugal force applied to the air and the pushing action imparted to the air by the blades 43, operates in still a third manner, that of squeezing the air 25 during a closing movement of pairs of blades 43.

Referring to Fig. 2 of the drawings, it is pointed out to the reader that the solid lines indicate the position of the blades 43 for the maximum opening at the top and also the position for 30 the minimum opening at the bottom. The angle of maximum opening is designated by the letter a and the angle of minimum opening is designated by the letter b . The capacity angle c at the top is the difference between angle a and angle b and is a measure of $\frac{1}{6}$ of the capacity 35 of the blower per revolution (C. P. R.), while $6 \times c$ is a measure of the total capacity of the blower per revolution (C. P. R.).

The setting for maximum capacity shown by 40 the solid lines on Fig. 2 is the setting wherein the push bars 57 are revolved inwardly as far as allowed by the slotted locking plates 62. The dotted lines on Fig. 2 represent the setting for minimum capacity wherein the push bars 57 are revolved as far outwardly as can be permitted by 45 the slotted locking plates 62. In the minimum capacity setting, the maximum opening is designated by a' , the minimum opening by b' , and the difference by angle c' , wherein c' is the measure of $\frac{1}{6}$ of the capacity per revolution of the blower.

There are many conditions in which it is desirable to change the capacity of the blower without changing its speed of rotation. It is, of 50 course, understood that the effective capacity of the blower may also be varied by the change in its rate of revolution. Actual working tests on the working model above referred to in this specification have shown that a high degree of efficiency in operation was maintained under higher than 50% variations in the rotating speeds of the blower.

In Fig. 1 of the drawings, the dotted line arrows indicate the direction of travel of the angular cylindrical section of air leaving the blade 65 43 at the position where the blade 43 is beginning to slow down. The section of air that has gained the maximum velocity of the blade 43 continues on under its own momentum and leaves the blade 43 which is slowing down. This volume of air, however, is compelled to travel under the curved crown 20 in a circular direction. This action of the pushing blade 43 on the air might be thought of as a slapping force on the air.

The blade 43 also turns the angular cylindrical

section of air confined between adjacent blades 43 in a direction in line with the straight cylindrical housing extension 17. The pushing blade 43 also, in approaching the blade 43 ahead of it, squeezes the angular cylindrical section of air out into the housing extension 17.

The shaft 30 may be set in a manner to decrease the air friction in installations wherein there is employed an upturned elbow housing extension 17' or a down-turned housing extension 17'' such as shown by the short and long dash lines of Fig. 1. The upturned housing extension 17' is outlined with short dash lines and the direction of the air approaching it is outlined with short dash arrows, while long dash lines are used to outline the down-turned housing extension 17'' and long dash arrows to indicate the flow of air toward it.

Experience in operating a working model of a blower made according to the disclosure of this specification showed under test that even when the straight housing extension 17 was used, the cross bar 32 should be set about 10 degrees back of vertical center line for best efficiency when the revolutions per minute of the cage 48 (R. P. M.)_c were between 50 and 125. I attribute this lag in operation to the inertia of the air itself.

Referring to the diagrammatic view, Fig. 4, letter C designates the linear velocity of the driving points of the cage 48 in feet per second.

$$C, \text{ in ft./sec.} = \frac{(R. P. M.)_c}{60} \times \frac{2\pi k}{12}$$

Where

(R. P. M.)_c = revolutions per minute of the driving points of the cage 48 about the cage axis of revolution O_c and which factor is constant. k = radial distance in inches between axis of revolution O_c of the cage 48 and the driving points of the cage 48 (pivot axes of the knuckle slide bearings 59). k is made a constant by means of the rocker arm locking means 61 during a continuous run of the blower.

The value of C as found by the calculation to follow and as shown by the dotted line polar graph of the same in Fig. 4 was determined from the known factors as follows wherein (R. P. M.)_c = 100 and k = 10 inches. Substituting these known values

$$C = \frac{100}{60} \times \frac{2\pi 10}{12} = 8.72 \text{ ft. per second}$$

Letter F designates the linear velocity of the extreme tip of the fan blades 43 and is found from the following equation:

$$F = \frac{(R. P. M.)_c}{60} \times \frac{2\pi l}{12}$$

$$F = \frac{(R. P. M.)_c}{60} \times \frac{2\pi l}{12} \times \frac{k(k+h \cos Q)}{m^2}$$

$$F = \frac{(R. P. M.)_c}{60} \times \frac{2\pi l}{12} \times \frac{k^2 - h^2 + m^2}{2m^2}$$

Where

Q = angle turned by the cage 48 as shown by the dotted line through k measured from a dotted line passing through the two centers of revolution O_c and O_t.

(R. P. M.)_c = revolution per minute of the fan blade 43 about its axis of revolution O_t. (R. P. M.)_c varies, as earlier explained, through a cycle of speeds. Its value at any degree of rotation is dictated by the position of the

knuckle slide bearing 59 on the guide rod 44 forming a part of the blade 43.

m = radial distance in inches from axis of revolution of the blade O_t to the driving point of the cage 48. This factor is a variable, the value of which is dictated by the position of the knuckle slide bearing 59 on the guide rod 44. The value of m varies from its minimum value when the blade 43 is extended directly upwardly along the 180° radius line as shown on the diagram of Fig. 4 to a maximum value when it is extended directly downwardly on the 0° radius line. Since the (R. P. M.)_c is maintained constant and k and l being fixed distances are therefore constant it can be seen from the equation that F varies proportionally to the value of the variable fraction.

$$\frac{k(k+h \cos Q)}{m^2} \quad \text{or} \quad \frac{k^2 - h^2 + m^2}{2m^2}$$

That is to say (R. P. M.)_c varies inversely to m², k being constant during an entire run of the blower.

Assuming the blade 43 to be at the 180° radial position, the position of maximum velocity as shown in Fig. 4, angle Q would be zero, making cos Q = 1 and

Where

$$30 \quad (R. P. M.)_c = 100$$

$$k = 10 \text{ inches}$$

$$m = 6 \text{ inches}$$

$$h = 4 \text{ inches}$$

$$l = 20 \text{ inches}$$

35 The value of the blade tip speed is found by a solution of the equation of F as follows:

$$F = \frac{(R. P. M.)_c}{60} \times \frac{2\pi l}{12} \times \frac{k^2 - h^2 + m^2}{2m^2}$$

40 Substituting known values in the equation:

$$F = \frac{100}{60} \times \frac{2\pi \times 20}{12} \times \frac{100 - 16 + 36}{2 \times 36} =$$

29.08 feet per second

45 When the blade 43 is at 0° radial position it is moving at its slowest speed. At this position, only the value m has changed: m at the 0° radius = 14 inches

$$50 \quad F = \frac{100}{60} \times \frac{40\pi}{12} \times \frac{10^2 - 4^2 + 14^2}{2(14^2)} = 12.46 \text{ feet per second}$$

The value of F may likewise be calculated for the other radial positions of the fan blades 43.

55 The capacity of my blower per revolution (C. P. R.) is determined by the maximum magnitude of the fraction m^{1/2}.

The value of k in the preferred form of blower may be varied for different runs of the blower as explained above through the means of the rocker arm locking means 61. An adjustment of the rocker arm locking means 61 effects a change in the radial distance k of the knuckle slide bearing from the axis of rotation of the cage O_c.

65 For convenience of comparison I have shown in Fig. 4 a polar diagrammatic plot of the linear speed of the driving points of the cage 48, dotted circle C, and superimposed on it, a polar plot of the linear speed of the tip of the blades 43, the solid line oval shaped curve, designated by letter F. Both curves are plotted on common radial ordinates emanating from the circle O_c and angularly measured abscissa. The reader should keep in mind, however, that the blades 43 are revolved about their own axis of rotation O_t which

70

axis is offset from the axis of rotation of the cage O_c by the distance h as seen in Fig. 5 of the drawing.

The distance h is one of the principal controlling factors in the design of blowers made under the teachings of my invention wherein a cage or other mechanical equivalent blade rotating means is used. The above statement applies both to the preferred embodiment of my blower illustrated by Figs. 1-5 and also to the modified form of my blower illustrated by Figs. 6-9 inclusive to be explained further on.

It is to be understood, however, that my invention in blowers is not to be limited to blower constructions that only incorporate cage type blade turning mechanisms or their mechanical equivalents for my inventive concept of blowers includes any mechanism adapted to rotate blades about a common axle at separately varying speeds in the useful manner above described.

Disregarding variations in the value of k , accomplished by the rocker arm locking means 61, the capacity of my preferred type blower illustrated by Figs. 1-5 is determined by the value of h . That is to say the capacity (C. P. R.) of the preferred form of blower is increased as h is increased, and vice versa.

My modified form of blower is illustrated by Figs. 6, 7, 8 and 9 of the drawings. The principal differences between this modified form of blower and the preferred form of blower resides in a link arrangement for driving its blades used in place of the knuckle bearings slide 59 and the guide rod 44 of the preferred form of blower.

The frame structure 100 includes a base 101 on which a pair of A frames 102 provided with top members 103 are mounted by means of bolts 104. Each A frame 102 is provided with a slotted middle brace 105. The housing 106 is provided with crown finger slots 107 and pan finger slots 108, an intake opening 109, and a discharge opening 110. The housing 106 is provided with a pair of rear feet 111 and a pair of forward feet 112 which are secured to the base 101 by means of bolts 113. A crown 114 and a pan 115 are rotatably mounted within the housing 106 by means of a pair of spiders 116 provided with a pair of upwardly extending arms 117 from which crown supporting fingers 118 are extended through the crown finger slots 107 and joined to the crown 114. The spiders 116 are provided also with forwardly extending arms 119 which arms 119 are provided with pan supporting fingers 120 extending through the pan finger slots 108 and joined to the pan 115. The spiders 116 are attached by means of set screws 121 directly to the shaft 122. The shaft 122 is adjustably, rotatably mounted in bearings 123 mounted on the top members 103 of the A frame 102 by means of bolts 124.

Shaft 122 is made exactly the same as the shaft 30 of the preferred form of blower in that it is provided with stud portions 125 adapted to fit in the bearings 123. The stud portions 125 are made integral with the disk portions 126 which are joined together by the cross bar 127. The stud portions 125 are provided with squared ends 128 on which adjusting levers 129 are mounted. The angular positions of the cross bar 127 of the shaft 122 are determined through the means of the adjusting levers 129 which are adapted to be clamped to the slotted middle braces 105 by clamping bolts 130 and clamping nuts 131.

The cage 132 in this modified form of blower is made substantially the same as the cage 48 75

of the preferred form of blower in that it is made up of a pair of centrally depressed side plates 132a joined together by means of spacing rods 134. The cage 132 as a unit is rotatably mounted on the stud portions 125 of the shaft 122 by means of roller bearings 135. The blades 136 are individually, rotatably mounted on the cross bar 127 through the means of pairs of bearing collars 137 to which the blades 136 are directly attached by means of supporting studs 138. The bearing collars 137 are properly positioned by guide collars 139 provided with set screws 140. An adjustable link bracket 141 is mounted on the rear side of each blade 136 by means of a pair of screws 142 which are screwed into a pair of threaded holes 143 made in the blade 136. In this modified form of blower the capacity may be changed by changing the position of the adjustable link brackets 141 on the blade 136. The pushing links 144 which are pivotally mounted on the link brackets 141 and pivotally mounted by means of their sleeve portions 145 at the centers of the spacing rods 134 are fixed in so far as length is concerned. This blower is driven by means of a pulley 146 and a belt 147 connected to a source of power not shown.

During the operation of this modified form of blower the pushing links 144 assume various angular positions in their plane of rotation as a result of their being pivoted to the blades 136 which separately rotate at varying speeds about the blade axis O'_c which is parallel to, but spaced from the axis of rotation of the cage O_c . The cage 132 pushes the blades 136 through the means of the links 144 for a clockwise rotary motion of the cage as shown in Fig. 6. When the cage 132 is rotated counterclockwise it pulls the blades 136 through the means of the pushing links 144. The operation of this modified form of blower will become more apparent from my discussion to follow of the diagrammatic views, Figs. 8 and 9, illustrating its mode of operation.

The capacity of the modified form of blower as in the preferred form of blower is measured by the differences between the maximum angle of opening A_2 and the angle of minimum opening B_2 which is angle C_2 . Since this modified blower has only six blades 136, $6 \times C_2$ is a measure of its capacity per revolution (C. P. R.).

The linear velocity of the cage driving points C' and the blade linear velocity of the blade tips F' in Fig. 8 are both plotted on the same radial ordinates and angularly measured abscissa. The driving points of the cage 132 in this modified form of blower are the center points of the center lines of the spacing rods 134.

$$C' \text{ in ft./sec.} = \frac{(R. P. M.)_c \times 2\pi k}{60 \times 12}$$

Where

$(R. P. M.)_c$ = revolutions per minute of the driving points of the cage 132 about the cage axis of revolution O'_c and which factor is constant.
 k = the radial distance in inches between the axis of rotation O'_c of the cage 132 and the driving points of the cage 132 and which factor is a constant.

The value of C' as shown by the calculation to follow and the dotted line polar graph of the same in Fig. 8 was determined from a condition wherein

$$(R. P. M.)_c = 100$$

$$k = 10$$

$$C' = \frac{100}{60} \times \frac{2\pi 10}{12} = 8.72 \text{ ft./sec.}$$

11

The value of F' which designates the linear velocity of the blade tip of a blade 136 of the modified blower for all of the positions of the blade 136 is shown by the polar graph in Fig. 8. The value of F' at any position of the blade 136 may be found from the following equations. Condition wherein link 144 pushes the blade 136

Wherein

R =radius of cage 132 to point where link 144 is fastened to it, measured in inches, a constant.

H =distance between centers of rotation of the cage O_c' and the center of rotation of the blades O_r' , measured in inches a constant.

M =distance from blade axis of rotation O_r' to point where link 144 is fastened to blade 136, measured in inches a constant.

S =length of link 144 measured in inches, a constant.

L =length of blade 136, measured in inches, constant.

U =angle turned by cage 132 from reference axis joining two centers of rotation O_c' and O_r' , a variable.

P =a constant angle whose value is given by

$$\cos P = \frac{(M-H)^2 + K^2 - S^2}{2K(M-H)}$$

As seen in the diagram of Fig. 9, P is the angle between the axis of reference, the dotted vertical line, and a line joining the axis of rotation of the cage O_c' to where the link 144 is fastened to the cage 132 when the blade 136 lies along the axis of reference.

$$D^2 = H^2 + K^2 + 2HK \cos (U - P)$$

which is a variable.

$$F' = \frac{(R.P.M.)_c K}{60D^2} \times \frac{2\pi L}{12} \left[K + H \cos (U - P) + \frac{H(D^2 + S^2 - M^2) \sin (U - P)}{\sqrt{4M^2S^2 - (S^2 + M^2D^2)^2}} \right]$$

Condition wherein length 144 pulls blade 136

$$F' = \frac{(R.P.M.)_c K}{60D^2} \times \frac{2\pi L}{12} \left[K + H \cos (U + P) - \frac{H(D^2 + S^2 - M^2) \sin (U + P)}{\sqrt{4M^2S^2 - (S^2 + M^2D^2)^2}} \right]$$

Any change in the dimensional factors in the equation set forth above will produce entirely different diagrams from the one shown in Fig. 8 of the drawing. Through the means of the velocity diagram of F' of the modified form of blower and the velocity diagram F of the preferred form of blower acceleration diagrams could be produced if desired as aids in the study of the forces acting on the various moving members of the blowers.

Various changes in the size and arrangement of the parts of the illustrated mechanisms may be resorted to within the scope of my invention. For example, the mother bearing collar 41 of the preferred form of blower may be incorporated in the modified form of blower in place of the bearing collar 137 found in the same, or the bearing collar 137 might be used in the preferred form of the blower.

The details of manufacturing my invention will present no problems to manufacturers engaged in the manufacture of other types of blowers, pumps, and similar mechanisms. I will point out, however, that due to the fact that since the blades 43 of the preferred form of blower, and the blades 136 of the modified form of blower are carried through rapid changes in their velocities, that these blade members should preferably be made out of a very light material such as aluminum.

Having thus described my invention I claim:

1. A blower mechanism comprising a support-

12

ing structure, a pair of stud shafts journaled on said supporting structure and aligned with each other, a disc carried by each of said stud shafts, a transverse bar extending between said discs in a position eccentric to the axes of said stud shafts, a multiplicity of bearing collars mounted on said bar, a cage including a pair of centrally depressed side plates recessed to house said discs, spacing rods extending at peripherally spaced intervals between the side plates of said cage around the recesses in said side plates, blades connected with the respective collars on said transverse bar, links pivoted at one of their ends with the spacing rods extending between said side plates and at the other ends thereof with the respective blades, and means for rotatably driving said cage around said discs.

2. A blower mechanism as set forth in claim 1 including means connected with each of said stud shafts for orienting said discs and the transverse bar extending therebetween for adjusting the relation of the centers of the connecting positions of said blades with said discs and the angular relation of said links between said blades and said spacing rods.

3. In a blower mechanism, the combination of a supporting structure, a housing provided with an intake opening and an exhaust opening mounted on said supporting structure, a set of two or more blades rotatably mounted on said supporting structure about a common axis of rotation and in circumferential alignment with one another inside of said housing, a blade rotating means comprising a rotatable member rotatably mounted on said supporting structure on an axis of rotation offset from the axis of rotation of

said blades, said blade rotating means includ-

ing driving members movably connected to said blades, a blade adjusting means adapted to angularly vary the position of said set of two or more blades about their axis of rotation when said blade rotation means is still for the purpose of varying the direction of air discharged by said blades, a pair of air sealing members consisting in a curved crown located near the top of said housing in close proximity to the circular path of the tip of said blades and a curved pan located near the bottom of said housing in close proximity to the path of the tip of said blades, said crown and said pan being rotatably mounted on said supporting structure on the axis of rotation of said set of two or more blades whereby said crown and said pan may be rotated within said housing to comply with angularly adjusted positions of said set of two or more blades, said blade rotating means being adapted to turn all of said blades consecutively through cycles of speeds continuously varying progressively from minimum speeds to maximum speeds and thence in progressively decreasing manners down to minimum speeds.

4. In a blower mechanism, the combination of a supporting structure including a pair of parallel upwardly extending side frames, a shaft extending transversely between said side frames, said shaft being made in the shape of a crank comprising a centrally positioned offset portion and a pair of outwardly extending spaced stud

shafts lying on a common center line offset from but parallel to said centrally positioned offset portion, said stud shafts being rigidly fastened to said side frames, a set of two or more blades pivotally mounted on said offset portion, a blade rotating means comprising a cage-like structure including a pair of spaced circular side plates rotatably mounted on said stud shafts, a plurality of circumferentially spaced spacing rods interconnecting said circular side plates, and elongated pushing bars pivotally mounted on said cage-like structure, each pushing bar having an end movably connected to one of said blades at a medial portion of the length of said blades.

5. A blower mechanism as set forth in claim 4 including a housing provided with a circular opening located to receive one of said side plates and wherein said side plate is provided with means for turning said blade rotating means.
